SLIDE FASTENER

Maurice Voity, Manhasset, N. Y., assignor to
 Serval Slide Fasteners, Inc., Flushing, N. Y., a
 corporation of New York

Application November 10, 1951, Serial No. 255,795

2 Claims. (Cl. 24—205.14)

1

This invention relates to slide fasteners.

More particularly my invention pertains to an automatic slider for slide fasteners, that is to say, a slider which automatically is detained against opening movement anywhere along a pair of stringers but is released for free movement in such direction simply by normal manipulation of the pull tab. Even more specifically my present invention relates to a pin lock slider of the character described.

Although sliders of this general type have been made and commercially used for many years they always have been relatively complex and expensive, unreliable in operation, and difficult to assemble. Usually such sliders consisted of four separately made parts whose assembly required a watchmaker's skill. Some sliders have been proposed which consisted of only three parts but these likewise required great manual dexterity to assemble and achieved a reduction in the number of parts by reducing the strength and increasing the complexity of some of the parts. For example the three part sliders employed a split bar pull tab which was far weaker inherently than a solid bar pull tab of the same dimensions. The three part sliders also used anchoring members shaped somewhat like lobster claws which, due to their shape, tended to deform during assembly and use.

It is an object of my invention to provide a slider of the character described which has only three parts and yet can be assembled with ease.

It is an object of my invention to provide a slider of the character described which has only three comparatively strong and simple parts.

It is another object of my invention to provide a three part slider of the character described which employs a solid bar pull tab.

It is another object of my invention to provide a three part slider of the character described which can be made at a comparatively low cost and yet is rugged, and smooth and efficient in operation.

Other objects of my invention will in part be obvious and in part will be pointed out herein-after.

My invention accordingly consists in the features of construction, combinations of elements and arrangements of parts which will be exemplified in the device hereinafter described and of which the scope of application will be indicated in the appended claims.

In the accompanying drawings in which is shown one of the various possible embodiments of my invention,

2

Fig. 1 is a fragmentary top view of a slide fastener including a slider constructed in accordance with my invention;

Fig. 2 is an enlarged longitudinal central sectional view taken substantially along the line 2—2 of Fig. 1, the slider stringers being omitted for clarity;

Figs. 3 and 4 are transverse and horizontal sectional views taken substantially along the lines 3—3 and 4—4 respectively of Fig. 2;

Fig. 5 is a top view of a slider body which constitutes one of the three parts of the slider shown in Fig. 1, said body being shown as it appears prior to incorporation thereof in a finished slider;

Fig. 6 is a side view of a bail which constitutes the second part of the slider shown in Fig. 1;

Figs. 7 and 8 are rear and front views respectively of the bail shown in Fig. 6; and

Fig. 9 is a perspective view of a pull tab which constitutes the third part of the slider shown in Fig. 1.

Referring now in detail to the drawings, the reference numeral 10 denotes a slide fastener comprising a conventional pair of stringers 12, each of which has secured along its beaded edge a set of standard slide fastener elements 14. A slider 16 is designed to move along the stringers, the configuration of the slider being such as is well known to the art, that when it is moved in the direction indicated by the arrow A it will mesh the elements 14 and when it moves in the opposite direction it will disengage said elements. These two directions are known, respectively, as the "closing" and "opening" directions.

The slider 16 is conventional in many respects. Thus, it includes a slider body 18 having an upper wing 20 and a lower wing 22 joined by a neck 24 which holds the wings in parallel spaced relationship. The side edges of the wings are provided with rails 26, the rails on the upper wing and the rails on the lower wing being in registry and all of the rails together with the neck conjointly defining a Y-shaped enclosure. Insofar as the slider body functions to engage and disengage slide fastener elements, that is to say insofar as the contour of its wings, rails and inner surface of its neck are concerned, said slider body is of standard construction.

However, pursuant to the present invention the slider body includes additional details to enable it to constitute one of the three parts of an easy-to-assemble, durable and inexpensive automatic pin lock slider. Thus, the upper wing 20 is provided with a tongue 28 which is struck up from

the material of said wing. The base of the tongue is integral with the upper wing near the center thereof and the tongue extends from its base toward the single opening end of the slider, i. e. away from the neck 24. This end of the slider, i. e. the neck end, is referred to herein as the "front" end and the opposite end as the "rear" end of the slider. The tongue runs along the end-to-end central axis of the wing and the tip 30 of the tongue is disposed a short distance inwardly from the rear end of the slider. The sides of the tongue are free of the upper wing so that the formation of the tongue leaves a long narrow notch 32 in said wing directly beneath the tongue. Said notch is broadened intermediate its ends by a pair of indentations 34 on opposite sides of the tongue. These indentations extend completely through the upper wing. The tongue is sloped upwardly away from the upper wing (see Fig. 2) to form a ramp portion 36 which covers almost the entire length of the tongue from its base to near its tip. This ramp portion has an inclination such that the tip 30 of the tongue has its lower surface approximately coplanar with the top surface of the upper wing, the tip of the tongue being substantially parallel to the upper wing.

Prior to assembly, the neck 24 of the slider body is formed to provide a narrow trough 38 extending in a direction transverse to the planes of the wings.

In further pursuance of my invention the slider includes a bail 40 which is fabricated from a sheet of resilient metal, e. g. beryllium copper or Phosphor bronze. The bail comprises an elongated narrow top wall 42 having downwardly extending flanges 44, 46 along its opposite side edges. On its rear edge the wall has a downwardly extending finger 48 and at its front edge a downwardly extending tail 50. In order to maintain maximum resiliency in the operation of the bail, as well as ease of manufacture, the bases of the finger and tail are integral, i. e. in one piece, with the opposite ends of the top wall 42, and are separated from the flanges 44, 46 by narrow slots 52.

The finger 48 extends rearwardly as well as downwardly from the rear edge of the top wall, as best seen in Fig. 2, and terminates in a forwardly extending tip, i. e. hook, 54. The distance from the top wall 42 to the hook is such that when the bail is assembled with the slider body 18, the hook will be below and spaced from the tip 30 of the tongue so that space is provided for upward movement of the hook.

The tail 50 extends forwardly as well as downwardly from the front edge of the top wall 42. Before the bail is assembled on the slider body the tail is inclined rearwardly to a slight degree as indicated in Fig. 6, in order that, after assembly, during which the tail is flexed forwardly, the bail will be biased against the upper wing. Said tail is formed with a pair of indentations 56 in its opposite front corners above its bottom end.

The lower edges of the two flanges 44, 46 are specially shaped. Each edge includes a section 58 and a section 60 disposed at the front and rear ends, respectively, of the bail, said sections being aligned with one another and being abutted against the top surface of the upper wing by a stress created in the tail during the mounting of the spring bail. The abutment of the sections with the upper wing defines the lowermost position of a pin lock soon to be described.

The lower edge of each flange further includes a central notch 62, the notches in said flange being in transverse alignment. Each notch comprises a forward edge 64 which is substantially perpendicular to the sections 58, 60, a cam section 66 which extends upwardly and forwardly from the top of the section 64, a section 68 which extends forwardly from the forward end of section 66 and is parallel to the sections 58, 60, and a section 70 which extends downwardly and forwardly from the forward end of section 68 to the rear of section 58.

In addition to the foregoing, the bottom edges of the flanges 44, 46 include locking pins 72, 74 between the notches 62 and sections 60, one pin 72 being integral with the flange 44 and the other pin with the flange 46. Each pin has a rear edge 76 which is perpendicular to the sections 58, 60 and a front edge 78 which is sloped upwardly and forwardly at a substantial angle, 45° being exemplary. The pins are not in transverse alignment but, as shown in Fig. 6, are longitudinally offset from one another. The amount of offset is one-half the center-to-center distance between slide fastener elements on a stringer.

The third and last element of the slider is a pull tab 80. One end 82 of the pull tab is the manipulative end, i. e. the end to be grasped by a user for moving the slider. The other end 84 of the pull tab is designed to engage the bail. This end is formed with a solid bar 86 joining the sides of the tab, the bar being formed by providing a through opening 88 in the pull tab.

To assemble the parts of the slider, the bail is threaded through the opening 88 in the pull tab until the bar 86 reaches the notches 62. Then the tip 54 of the bail finger 48 is hooked under the tip 30 of the tongue 28 and the bail swung about the interengaged tips until the tail 50 is seated in the trough 38. To facilitate such seating, the trough is formed with square bottom corners 90 against which the edges of the bail are abutted. At this time the indentations 56 are located within the neck of the slider.

As thus far described the assembly of the three slider parts can be performed by hand without requiring the exercise of unusual manual dexterity.

Lastly the trough 38 is squeezed about the tail 50. This operation is performed in a suitable clamping machine which engages the outer side walls of the neck and squeezes the same together forcing metal from the neck into the indentations 56 and thereby preventing the bail from being disengaged accidentally from the slider body. The machine in which the neck is squeezed desirably is provided with means to force the bail down against the top surface of the upper wing 20, i. e. to force the sections 58, 60 of the flanges 44, 46 against the top surface of the upper wing, before the neck is squeezed. Also at or prior to squeezing the neck, the bail is forced forwardly so as to flex the tail 50 until the same is in a more erect position, e. g. perpendicular to the upper wing, the bail being in such position as the slider neck is squeezed about the tail, whereby the finger 48 permanently is biased downwardly and the locking pins 72, 74 permanently biased against slide fastener elements 14 on the stringers 12.

Normally, i. e. when the pull tab is unactuated, the biasing force just described will maintain the locking pins 72, 74 in the spaces between adjacent slide fastener elements. If the stringers

are spread apart, the perpendicular edges 76 of the locking pins will abut squarely against the sides of slide fastener elements and thus prevent the slider from moving in an opening direction, although because of the slope of the edges 78 the slider can be moved in a closing direction by urging the slider body in such direction with or without manipulating the pull tab. The only way the slider can be moved in an opening direction is by pulling on the tab 80 as one normally would to move the slider in such fashion. This manipulation of the pull tab causes the solid bar 86 to ride up the ramp 36 and engage the cam sections 62 of the two flanges 44, 46 thereby flexing the tail 50 and swinging the bail away from the upper wing until the hook 54 strikes the tip 39 of finger 28. By this action the locking pins 72, 74 are lifted clear of the underlying slide fastener elements so that the slider can move in an opening direction. When the pull tab is released the bar 86 will ride down the ramp 36 into the middle of the notches 62 where sufficient clearance is provided (see Fig. 2) to enable the bail to abut against the top surfaces of the upper wing so that the locking pins again can be effective.

It thus will be seen that there is provided a device which achieves all the objects of the invention and is well adapted to meet the conditions of practical use.

As various possible embodiments might be made of the above invention, and as various changes might be made in the embodiment above set forth, it is to be understood that all matter herein described, or shown in the accompanying drawings, is to be interpreted as illustrative and not in a limiting sense.

Having thus described my invention, I claim as new and desire to secure by Letters Patent:

1. An automatic lock slider consisting of a slider body, a bail fabricated from resilient sheet metal, and a pull tab, said slider body including an upper and a lower wing joined by a neck, a tongue in one piece with the upper wing and sloped outwardly therefrom toward the single exit end of the slider, the sides and tip of the tongue being free of said wing, there being openings in the upper wing on opposite sides of the tongue, said neck having a trough extending in a direction between the wings, said bail comprising an elongated top wall overlying the tongue, a finger integral with and extending away from an end of the top wall, the tip of said finger being hooked and disposed beneath and spaced from the tip of the tongue, said bail also including a tail integrally extending away from the opposite end of the top wall, said tail including an indentation, the tail being received in the trough and stressed to bias the bail toward the upper wing, the walls of said trough engaging the indentation whereby to captively embrace the tail, said bail having a pair of flanges in one piece with the top wall and extending downwardly toward the slider body, the bottom

edges of said flanges being biased by the tail into abutment with the top surface of the upper wing, each of said flanges including a locking pin, said pins projecting through the openings in the upper wing and being biased by the tail into engagement with slide fastener elements of a stringer extending through the slider body, the bottom edges of said flanges having notches, the forward portion of the upper edge of each notch being sloped towards the upper wing, said pull tab having a solid bar captively held in the notches between the bail and the upper wing, said solid bar riding against the sloped tongue and the sloped notch portions when the pull tab is urged in an opening direction whereby to lift the pins out of engagement with slide fastener elements, the disengaging movement of the bail being limited by engagement between the tips of the finger and tongue.

2. An automatic lock slider consisting of a slider body, a bail lock fabricated of springy sheet metal, and a pull tab, said slider body including an upper and a lower wing joined by a neck, a tongue in one piece with the upper wing and sloped outwardly therefrom toward the single exit end of the slider whereby the tongue includes a tip and a ramp, said wing having an opening alongside the tongue, said neck having a trough extending in a direction between the wings, said bail including a finger having a hooked tip disposed beneath and spaced from the tip of the tongue, said bail also including a tail received in the trough and stressed to bias the bail toward the upper wing, the walls of said trough captively engaging the tail, said bail including sides each of whose lower edges has a notch including a cam portion above the ramp, said bail further including a pin which projects through the opening in the slider wing and is biased by the tail into engagement with slide fastener elements of a stringer extending through the slider body, said pull tab having a solid bar captively held between the bail and upper wing, said solid bar riding against the ramp and engaging said cam portions when the pull tab is urged in an opening direction whereby to raise the bail and lift the pin out of engagement with slide fastener elements, the raising movement of the bail being limited by engagement between the tips of the finger and tongue.
